DESIGN FOR A CHILD'S WHEELED VEHICLE

Edward C. Huebner, Detroit, Mich.

Application November 23, 1945, Serial No. 124,001

Term of patent 14 years

(Cl. D34—15)

To all whom it may concern:

Be it known that I, Edward C. Huebner, a citizen of the United States, residing at Detroit, in the county of Wayne and State of Michigan, have invented a new, original, and ornamental Design for a Child's Wheeled Vehicle, of which the following is a specification, reference being had to the accompanying drawing, forming part thereof.

Fig. 1 is a perspective view of the child's wheeled vehicle looking from a rear angle and showing the new design.

Fig. 2 is a perspective view of the child's wheeled vehicle looking from a front angle and showing the new design.

I claim:

The ornamental design for a child's wheeled vehicle, substantially as shown.

EDWARD C. HUEBNER.
